P. NATHANSON ET AL

SHUTTLE GUARD FOR LOOMS

Filed April 16, 1924

*Peter Nathanson,
Jacob Sonntag,
By their Attorney, Leo. M. Maitz*

UNITED STATES PATENT OFFICE.

PHILIP NATHANSON AND JACOB SONTAG, OF ALLENTOWN, PENNSYLVANIA.

SHUTTLE GUARD FOR LOOMS.

Application filed April 16, 1924. Serial No. 706,812.

To all whom it may concern:

Be it known that we, PHILIP NATHANSON and JACOB SONTAG, both citizens of the United States, and residents of Allentown, 5 in the county of Lehigh and State of Pennsylvania, have invented certain new and useful Improvements in Shuttle Guards for Looms, of which the following is a specification sufficient to enable those skilled in the art to which the invention appertains to utilize the same.

Our improvements relate to looms generally, but especially to those used in the manufacture of silk fabrics; and are designed to effectually eliminate dangers heretofore incidental to unintentional shuttle displacement or "flying" out of its prescribed course. As is well known in the prior state of the art, the hazard of a flying 20 shuttle is a serious matter, owing to the speed and impetus imparted thereto in effecting its reciprocatory across the baton, the free moving shuttle being easily deflected from its proper alignment, as by the 25 slightest impediment falling into the silk in front of the harness, or a broken end lying crosswise of the silk, or for any cause that will make the shuttle fly upward and off the loom, in which case the weight and momentum 30 of the travelling shuttle may result in serious injury.

For instance, should a shuttle so deflected out of its proper course strike an adjoining loom it is apt to smash the reed thereof, or 35 puncture holes in the cloth, or be itself destroyed by contact with extraneous objects, so that it not only involves risk of personal safety to those in proximity but involves also an item of expense and loss.

40 These difficulties and danger we obviate by our improved design of shuttle guard, our invention consisting in the specific construction, combination and arrangement of parts and appurtenances described and 45 claimed, whereby these and other advantageous results are attained, all as hereinafter fully set forth.

In the accompanying drawings we illustrate a practical embodiment of the essential 50 features of our invention in combination with a silk loom of a type well known in the art, although we do not limit ourselves to the identical form and construction of the component parts of our shuttle guard shown 55 herein by way of exemplification, since mod-

ifications in minor details, and equivalent mechanical expedients, may be resorted to with like results and without departing from the spirit and intent of our invention in this respect.

With this understanding:

Fig. 1, represents a front view, broken away medially, of our improved shuttle guard and adjacent parts of the loom to which applied;

Fig. 2, is an elevation, upon a larger scale, of the left end of the reed cap and guard, the latter being lowered into operative position;

Fig. 3, is a front elevation of the left end 70 of the reed cap, guard, etc., in the position shown in Fig. 2;

Fig. 4, is a view like unto Fig. 2, showing the guard raised;

Fig. 5, is a view like unto Fig. 3, showing 75 the guard raised;

Fig. 6, is a top view of the parts shown in Fig. 4;

Fig. 7, is a perspective view thereof.

In the drawings R, represents the usual 80 raceway or baton over which the shuttle S, is reciprocated in a manner and by means well known in the art,—B, B, being the shuttle boxes of customary construction and function.

K, is the usual reed cap or bar, on which our shuttle guard G, is mounted by means of brackets k, k, positioned near the extremities of said reed cap K, as shown more particularly in Fig. 1, of the drawings,

these brackets k, k, are preferably, although not necessarily, made of sheet metal of suitable thickness bent into shape, each with a base flange k', for attachment to the reed cap K, and with a bearing plate k², projecting substantially at right angles to the said

base flange k', said bearing plate k², being in each case formed with a lateral guide or deflector k³, extending downward and in the direction of the box B, adjacent to its end of the reed cap K, also as shown more

particularly in said Fig. 1, of the drawings,—said deflectors k³, constituting important adjunctive features in connection

with our shuttle guard, considering the device in a unitary sense, in that they insure the entrance of the shuttle S, into said adjacent boxes B, at the termination of each reciprocatory stroke of the shuttle S, over

the baton R.

The guard bars g, g, preferably three in

number, are rigidly secured at their extremities to slide members g' , g' , which latter are mounted on the bearing plates k^2 , k^2 , of the brackets k , by means which admit of the raising and lowering of the shuttle guard G , within prescribed limits. This mobile mounting of the shuttle guard G , may be effected by resort to various mechanical expedients, equivalents of the specific construction and arrangement of parts shown in the drawings, in which the slide members or end plates g' , g' , of the guard G , are formed with slots g^2 , g^2 , for the accommodation of the headed retaining pins k^x k^x , which confine the said end pieces g' , g' , of the guard G , to the brackets k , k , while admitting of their adjustment thereon. In this connection it is obvious, for instance, that an alternative arrangement of guard mount might be resorted to with like results, in that the bearing plates k^2 , k^2 , might be slotted, and the engaging retaining pins might be positioned on the end pieces or slides g' , g' , of the guard G . In either case the slots g^2 , would be provided each with a lateral offset, notch, or shoulder g^x , (see Fig. 2) for engagement with the lower retaining pin k^x , when the guard G , is elevated in position as shown in Figs. 4 and 5,—it being understood that the slide members g' , are inclined in position substantially as shown, so that the weight of the guard G , will tend to maintain this engagement between the notch g^x , and the retaining pin k^x , while the guard is elevated, and at rest in that position, but will not withstand the vibration and jar incidental to the operation of the shuttle mechanism which will cause disengagement of this gravity catch device and allow the guard G , to descend automatically into operative position in so far as the reciprocatory path of the shuttle is concerned, when the loom is working, in which normal position of the guard G , its lower bar or edge extends approximately an inch or so from the cloth weave, thereby effectually screening the shuttle and confining it against lateral displacement from its prescribed course. Nevertheless, when the loom is at rest, the operator can raise the guard G , into the locked position above set forth if

he desires access temporarily to the rear thereof; and the operator need not necessarily lower the guard thereafter, since the renewal of movement of the operative parts of the loom will return the guard to normal position.

From the foregoing it will be seen that we attain substantial advantages by our improved construction and arrangement of shuttle guard and appurtenances, in that it is practically impossible for the shuttle to deviate from its prescribed course and leave the loom, and its delivery to the shuttle boxes is assured; that the guard when raised to give access to parts beyond will stay up without being held manually so long as the loom is at rest; and that the loom can in no case be left unguarded during operation, since the raised guard will automatically return to normal position as required, thus eliminating the need of attention by the operator to that extent.

What we claim as our invention and desire to secure by Letters Patent, is:—

1. A shuttle guard of the character designated, formed with a plurality of longitudinal bars rigidly attached to end members slidably mounted on brackets secured to the reed cap and all movable in unison, said brackets, and gravity latch means interposed between said brackets and said slidable members of the guard, one side of the guard being capable of being raised independently of the other side, substantially in the manner and for the purpose set forth: 75

2. A shuttle guard of the character designated, formed with a plurality of longitudinal bars rigidly attached to end members slidably mounted on brackets secured to the reed cap and all movable in unison, said brackets formed with rigid shuttle deflecting extensions, and gravity latch means connecting said brackets and said slidable end members of the guard, said guard being constructed to terminate substantially below the upper edge of the reed bar, when in raised position, substantially in the manner and for the purpose set forth. 95

PHILIP NATHANSON.
JACOB SONTAG.
